UNITED STATES PATENT OFFICE.

LEO F. ADT, OF TROY, NEW YORK.

DESIGN FOR A BOW-SPRING FOR EYEGLASSES.

SPECIFICATION forming part of Design No. 33,244, dated September 25, 1900.

Application filed August 18, 1900. Serial No. 27,351. Term of patent 14 years.

To all whom it may concern:

Be it known that I, LEO F. ADT, a citizen of the United States, residing at Troy, in the county of Rensselaer and State of New York, 5 have invented and produced a new and original Design for Bow-Springs for Eyeglasses; and I do hereby declare the following to be a full, clear, and exact description of the same, reference being had to the accompanying 10 drawings, forming a part thereof.

Figure 1 is a front view of a bow-spring for eyeglasses, showing my new design. Fig. 2 is an end view of the same. Fig. 3 is a plan view of such bow-spring.

15 As shown in the drawings, the leading or material features of my design consist of a

bow-spring A, having a curved central portion a, loop ends a', and offset extremities b. The central portion a is curved upward from the loop ends a' in an inclined plane, as shown 20 in Fig. 2.

Having described my invention, what I claim, and desire to secure by Letters Patent, is—

The design for a bow-spring for eyeglasses, 25 as herein shown and described.

In testimony whereof I affix my signature in presence of two witnesses.

LEO F. ADT.
